UNITED STATES PATENT OFFICE

EDWIN W. NORTH, OF ROCKFORD, ILLINOIS, ASSIGNOR TO NATIONAL LOCK CO., OF
ROCKFORD, ILLINOIS, A CORPORATION OF DELAWARE

LOCK

Application filed June 24, 1929. Serial No. 373,097.

This invention pertains to locks or latches for kitchen cabinets, refrigerators and the like and more particularly to invisible or concealed locks or latches for such purposes.

5 For convenience the invention will be described in connection with a refrigerator cabinet.

The majority of modern refrigerators, particularly those made for mechanical refrigeration, are either made of all metal construction or metal covered wood framing.

10 Such construction introduces a problem to prevent conduction of heat to the interior of refrigerating cabinets because most metals are very good conductors of heat. Any metal parts extending from the interior to the exterior of a refrigerator will conduct heat, and for this reason resort is had to various expensive constructions to insulate the interior

15 from the exterior. The edges of the door frame or of the door of a refrigerator are ordinarily provided with a felt or rubber strip to prevent any leakage of air to or from the refrigerator between the door and frame, and

20 in case the refrigerator cabinet is made of metal or of wood covered with metal, the metal on the inside is parted from the metal on the outside about any door opening by a strip of bakelite or other insulating material

25 to prevent direct conduction of heat.

It is highly desirable to have the refrigerator and other cabinet hardware concealed as much as possible, not only for æsthetic reasons, but also for mechanical and other

30 utilitarian purposes but, because such hardware including locks or latches and hinges must be made of metal, and as metal conducts heat, it is not always practical or advisable to conceal it within the door and door frame structures of refrigerators.

35 One of the primary objects of the invention is to provide a lock or latch and a keeper or strike peculiarly adapted to concealed use on refrigerating cabinets and the like particularly those made of all metal construction or made with metal covered wood frames. In this connection it will be appreciated that the invention is valuable for uses other than on refrigerators.

40 Another object is to provide a lock or latch

of the concealed type that will be self-locking or latching upon closing the door to which it is attached. An arrangement is provided whereby the lock or latch is normally secured in unlocked or unlatched position whenever the door is open.

45 Another object is to provide a self-locking or self-latching lock or latch that will not interfere with any rubber or any other material gasket or insulating strip used about the door frame or opening.

50 A still further object is to provide a lock or latch of the character described so constructed and arranged that it may be easily and quickly operated by merely rotating a handle, the handle serving not only to release the lock or latch, but also to open and close the door to which it is attached.

55 Many further objects as well as the advantages and uses of the invention will be or should become clearly appreciated and understood after reading the following description and claims and after viewing the drawing in which:

60 Fig. 1 is a transverse section through a corner of a refrigerating cabinet of the metal type showing one form of the invention applied thereto.

65 Fig. 2 is a front elevation partly of a section of the lock or latch shown in Fig. 1, the view being taken substantially along the line 2-2 of Fig. 1.

70 Fig. 3 is an end view of the keeper engaging portion of the lock or latch, and

75 Fig. 4 is a front elevational view of the keeper or strike illustrated in Fig. 1.

80 The refrigerating cabinet proper is generally designated 2 and is formed of sheet steel or other sheet metal as may be desired. A portion of the sheet metal frame may be formed as shown between the reference characters 3, 3 to provide a door framing about the door opening, adapted to be closed by door 4 hinged at one side of the framing 3 in any suitable manner. The door 4, in the embodiment illustrated, is also made of sheet steel or other suitable material.

85 A striker or keeper 6 is secured as by bolts, screws or rivets 7 within a shouldered recess 8 in the frame 3 and is preferably of the con-

struction illustrated in the drawing. This construction includes a portion of channel shape in cross section with the outer leg 9 somewhat shorter than the inner leg 11, the outer leg having a rounded corner 12 and a gently tapered inner surface 13. The leg 11 of the channel is divided midway of its length by an inwardly projecting rib 14 which terminates at the mouth of the channel 10 in a projection 15 extending slightly transversely of the mouth of the channel.

The sheet metal of the door is cut away opposite the keeper or strike 6 in order to receive a metal casing or shell composed of 15 telescoping parts generally designated 16 and 17 within which the lock bolt and part of its operating mechanism are contained. The two parts of the casing or shell are provided with registering flanges 18 and 20 19 respectively and are drilled with registering apertures 21 through which bolts, screws or other securing means are passed to secure it to the sheet metal of the door 4. The casing part 17 is provided with an in-turned 25 portion 22 for purposes to be described.

A bolt generally designated 23 is slidably or reciprocably mounted within the casing and is normally urged out of the casing and toward the rear side thereof by a spring 24 30 abutting at one end in a recess 25 in the bolt and at its other end against the interior of the casing or shell, a screw 26 projecting through the rear wall of the casing serving to center and aid in retaining the spring. The bolt is 35 also provided with a recess 27 and an aperture 28 entering recess 27, the recess and aperture receiving a dog or bolt operating member 29 rigidly secured to a stem 31 rotatably mounted in the casing and non-rotatably mounted in the dog. The outer end of 40 the stem 31 is rigidly secured to a handle 32 about the outer end of which an escutcheon plate or sleeve 33 is disposed for protection purposes. The stem 31 between the sheet 45 metal of the outer side of the door and the lock casing is surrounded by a sleeve 34 to prevent insulation material from entering the working parts of the lock, while a coiled spring 35 surrounds the inner end of the stem 50 31 and is secured at one end to the stem and at its other end to the casing. The coiled spring 35 tends to return the handle to its normal position as well as taking up lost motion between the associated parts.

55 The keeper engaging end of the bolt is notched out as shown at 36 to provide a shoulder 37 adapted to engage behind the in-turned portion 22 of the casing when the bolt is in a retracted position. The bolt at 60 its interior end is provided with a projection or rib 38 serving as a pivot to insure movement of the shoulder 37 behind the projection 22 under the influence of spring 24. The keeper or strike engaging end of the 65 bolt or lock is formed as best shown in Figs.

2 and 3 to provide similar portions 39 between which a roller 41 is mounted on a pivot pin 42. The portions 39 have inwardly and rearwardly inclined surfaces 43 and terminate in projections 44, which projections 70 clear the keeper by a slight margin in order that the projections will not engage the keeper upon that side. The door is provided with a rim portion 45, the interior of which is channelled as shown at 46 to receive a rubber or felt gasket 47 which is secured therein in any suitable manner. The gasket 47 when the door is closed, abuts against a portion of the frame 3 above the keeper or strike, and then against the outer leg 9 of the keeper or 80 strike to the opposite end thereof and then continues on abutting against the frame below the keeper.

In operation, the door being closed, the handle 32 is rotated in a clock-wise direction 85 withdrawing bolt from the keeper and retracting it into the casing. As the bolt is retracted the shoulder 37 engages behind the in-turned portion 22 and secures the bolt in such position until the door is again shut or 90 until the bolt is otherwise tripped. As the door is moved to closed position, the roller strikes the projection 15 and disengages the shoulder 37 from behind the in-turned portion 22 of the casing permitting the spring 24 to 95 urge the bolt into the keeper. As the bolt rides into the keeper, the roller, riding along inclined surface 13, urges the door into tighter closed position. Should the bolt be released and occupy a projected position when 100 the door is open, upon closing the door the surfaces 43 of the portions 39 will engage the rounded shoulder 12 on the leg 9 and urge the bolt backwardly against the spring 24 and permit it to snap into the keeper. It will 105 be noted that the gasket 47 does not interfere with the latch or lock and that the latch or lock does not interfere with the gasket. Furthermore, the latch is not only simple and economical to manufacture, but may be 110 quickly and easily manipulated.

While I have illustrated and described a preferred embodiment of the invention, it will be appreciated that many changes and variations may be made therein without departing from the spirit of the invention and the scope of the appended claims.

I claim:

1. In combination with a door frame providing an opening and a door adjacent said frame for closing said opening, a bolt casing secured to said door, a keeper secured to said frame, a bolt slidably mounted in said casing, a spring normally urging said bolt toward keeper engaging position, means for disengaging said bolt from said keeper, means for securing said bolt in disengaged position, a rotatable element mounted upon said bolt for engagement with and disengagement from said keeper, means on said keeper 120 125 130

- in the normal path of said element as said door is closed for striking said element and releasing said bolt securing means, and means including an inclined surface on said bolt 5 adapted to engage a portion of said keeper for retracting said bolt when the door is being closed and said securing means is inoperative.
2. As an article of manufacture, a lock bolt comprising a bar adapted to be slidably disposed in a casing, one end of said bar being adapted to engage a keeper, said end having an inclined guiding surface and a roller mounted adjacent said surface.
- 10 3. As an article of manufacture, a lock bolt comprising a substantially rectangular bar adapted to be slidably disposed in a casing, a roller mounted on one end of said bar on an axis transverse the length of the bar 20 for rolling engagement with a keeper, and a portion of said end adjacent said roller having a guiding surface inclined outward and backward from said roller and toward the opposite end of the bar.
- 25 4. The combination with a recessed door frame providing an opening and a door adjacent said frame for closing said opening, of a concealed latch for said door comprising a bolt casing secured to said door within 30 the outer overlapping surface thereof, a keeper secured to said frame within the recess therein and having a portion thereof in the path of movement of a portion of the door, a bolt slidably mounted in said casing, a spring normally urging said bolt toward keeper-engaging position, means for disengaging said bolt from said keeper, means for securing said bolt in disengaged 35 position, a rotatable element mounted upon said bolt for engagement with and disengagement from said keeper, and means on said keeper in the normal path of said rotatable element as said door is closed for striking said element and releasing said bolt securing 40 means.
- 45 In witness of the foregoing I affix my signature.

EDWIN W. NORTH.
